DESIGN FOR A BROOCH

William Regelmann, Cranston, R. I.

Application January 31, 1941, Serial No. 98,627

Term of patent 3½ years

To all whom it may concern:

Be it known that I, William Regelmann, a citizen of the United States, residing at Cranston, in the county of Providence and State of Rhode Island, have invented a new, original, and ornamental Design for a Brooch, of which the following is a specification, reference being had to the accompanying drawing, constituting a part thereof.

Fig. 1 is a front elevation of a brooch showing my new design; and

Fig. 2 is a side elevation thereof.

I claim:

The ornamental design for a brooch, substantially as shown.

WILLIAM REGELMANN.
